(57) **CLAIM**

The ornamental design for a dehumidifier, as shown and described.

DESCRIPTION

FIG. 1 is a front perspective view of a dehumidifier; FIG. 2 is a view of the dehumidifier shown in FIG. 1 from the front;

FIG. 3 is a view of the dehumidifier shown in FIG. 1 from the rear;

FIG. 4 is a view of the dehumidifier shown in FIG. 1 from the left;

FIG. 5 is a view of the dehumidifier shown in FIG. 1 from the right; and,

FIG. 6 is a view of the dehumidifier shown in FIG. 1 from the top.

The broken lines depict portions of the dehumidifier that form no part of the claimed design.

1 Claim, 6 Drawing Sheets
